Primary Examiner — Clare E Heflin(74) *Attorney, Agent, or Firm* — Georgi Korobanov(57) **CLAIM**

The ornamental design for a solar garden decoration light, as shown and described.

DESCRIPTION

FIG. 1 is a perspective view of a solar garden decoration light showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged fragmentary view taken from the circle 8 in FIG. 1.

The evenly-broken lines where present illustrate portions of the solar garden decoration light that form no part of the claimed design.
